UNITED STATES PATENT OFFICE.

HARMON O. NELSON, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

COMBER DOFFER-BRUSH.

1,265,810.

Specification of Letters Patent. Patented May 14, 1918.

Application filed July 29, 1915, Serial No. 42,436. Renewed March 28, 1918. Serial No. 225,365.

To all whom it may concern:

Be it known that I, HARMON O. NELSON, a citizen of the United States, residing at Whitinsville, in the county of Worcester 5 and State of Massachusetts, have invented the following described Improvements in Comber Doffer-Brushes.

It has heretofore been proposed to make the scavenger brushes of cotton combers in 10 two halves or sections capable of application to and removal from the rotary comber brush shaft without removal of the latter from the machine. Such a scavenger brush is shown in the application of E. A. Rooney, filed August 10, 1914, Ser. No. 855,967. In 15 that brush and in some others which are not removable, crevices are present in the end faces of the hubs of the brushes between the united sections, into which crevices and upon the entrance thereto, cotton fly and 20 lint collects to a very objectionable extent, and these accumulations if not properly removed work up into the comb cylinder and thence enter the combed lap, to its serious 25 impairment. Rounding or smoothing of the margins of the crevices does not suffice to remedy the difficulty, nor can it be corrected by fitting the sections more accurately together and to the brush shaft because of the 30 clearance that is necessary in order to get a firmly clamped connection. I have succeeded in preventing the accumulation of 35 lint at the brush hubs of removable sectional brushes, such, for example, as shown in the application referred to, by providing the clamping ring with a shroud flange which fits the brush shaft snugly and covers up the hub crevices, leaving no opening whatever in the end face of the brush and no 40 opening elsewhere on the hub, which will collect lint or fly. This effect is apparently due to the obstruction by the shroud flange of the air passage through the space or crevice between the opposing hub sections 45 and the elimination of all passages elsewhere into which air may be drawn when the brush is in action. The invention thus consists in the organization of the separable brush connections with a shroud flange on 50 the locking ring which fits the brush shaft and obstructs inward movement of air through or between the assembled parts of the hub, as will more fully appear from the accompanying drawings, in which—

55 Figure 1 represents an elevation of a

comber doffer brush with intermediate parts broken away and with one end shown in section.

Fig. 2 is a section on line II—II of Fig. 1, showing the shroud flange in elevation; 60 and

Fig. 3 is an elevation of the two ends of the brush sections before the ring and shroud flange are applied.

The brush shaft is marked 1, and is to be 65 understood as the usual brush shaft in Heilmann type cotton combers, which besides rotating, has an endwise traverse movement intended to cause the brush to wear evenly. The journals 2, in which this shaft is mounted, 70 are separated from each other far enough to accommodate such endwise traverse and also far enough to permit the locking rings 3 to be slipped off of the brush stock hubs at one end or the other, as will 75 later appear. The cylindrical brush 4 is formed of two semi-cylindrical brush stocks 5, made of wood, and provided with circular rabbets 6 at their ends. Semi-circular shoes 7 are fitted to these rabbets and held to the 80 ends of the wooden stocks by means of screws 8, as indicated more particularly in Fig. 3. When the two brush stocks thus equipped with semi-circular metal shoes at their opposite ends are placed upon and 85 around the brush shaft, the locking rings 3 are then slipped over the shoes and pushed into contact with the end wall of the wooden rabbet 6, whereupon the set screws 9 in the 90 said ring are screwed inwardly finding a durable bearing against the metallic shoes 7, and clamping them firmly upon the shaft. The locking rings 3 are formed in one piece with their shroud flanges 3^a, and the latter are fitted to the brush shaft and assembled 95 in pairs thereon between the bearings 2, when the brush shaft is installed in the frame of the comber. When secured to the 100 shoes, as shown in Figs. 1 and 2, they completely cover the otherwise open crevices indicated at 10 in Fig. 2, between the opposing metallic shoes 7, and by reason of the close contact between the locking ring and the shaft, as well as with the wall of the rabbet, all access of air into or from the 105 crevices between the parts of the assembled hub are effectually closed. The tapped holes for the set screws 9 being occupied completely by the latter, do not accumulate lint, and inasmuch as these screws are disposed 110

- in the peripheral face of the locking ring, they are readily accessible from the rear of the comber. Whenever it is desired to remove the brush, these screws are loosened, 5 the rings slipped off the shoes and the brush sections separated. By designing the rings of about the width indicated, ample clearance for the latter purpose is available without shortening the length of the brush.
10. It will be observed that the wooden brush stocks do not of themselves have contact with the brush shaft but are held thereon solely through the intervention of the metallic shoes 7, which are clamped to the 15 shaft by the locking ring, and it will also be noted that the locking ring is centered on the shaft, by the engagement of its shroud flange therewith, both of which conditions serve to center and secure the cylindrical 20 brush on the shaft in a superior manner, while at the same time permitting ready removal.
- Having described my invention, what is claimed as new is:
25. 1. The combination in a cotton comber of the doffer brush shaft and the doffer brush thereon arranged to be removable therefrom without withdrawal of the latter from the machine, and comprising two 30 brush-stocks shaped to surround the brush shaft, each stock having metallic shoes permanently secured to its opposite ends, a pair of locking rings encircling the shaft and adapted to removably engage adjacent 35 shoes on the assembled stocks, and shroud flanges on said rings obstructing entrance of air to the crevices between said adjacent shoes.
2. The combination in a cotton comber of 40 a doffer-brush shaft, a doffer brush thereon adapted to be removed therefrom without withdrawal of the latter from the comber and comprised of a plurality of assembled brush-stocks adapted to surround the brush
- shaft, each brush stock being provided with 45 metal shoes secured in rabbet grooves at its opposite ends, a locking ring having a shroud flange fitted to the brush shaft, said ring being adapted to be slid along the said shaft and slipped on and off the metal shoes 50 and provided with means for clamping said shoes against the shaft.
3. The combination in a cotton comber of a doffer brush shaft, a doffer brush thereon comprising two brush stocks embracing the 55 brush shaft, each having metallic shoes permanently secured to its opposie ends, and said shoes being adapted to engage the shaft, a pair of locking rings encircling the shaft and adapted to engage the adjacent 60 shoes on the assembled brush stocks, said rings having shroud flanges integrally formed thereon and adapted to obstruct entrance of air to the crevices between said shoes, and a set screw in the peripheral face 65 of each ring adapted to engage said shoes to clamp the same upon the shaft.
4. The combination in a cotton comber, a doffer brush shaft, a doffer brush thereon and removable therefrom without withdraw- 70 ing said shaft from the comber, said brush being composed of two brush-stocks each provided with metal shoes secured in rabbet grooves at its opposite ends, a locking ring having a shroud flange fitted to the brush 75 shaft, said ring being adapted to engage the metal shoes and the end wall of the rabbet groove, and provided with means on its peripheral face for clamping said shoes against the shaft, whereby the shroud there- 80 of covers the crevices in the adjacent shoes.

In testimony whereof, I have signed this specification in the presence of two witnesses.

HARMON O. NELSON.
